Patented Jan. 30, 1973

226,200

STANCHION

Aaron I. Friedman, Kentfield, Calif.
(325 Minna St., San Francisco, Calif. 94103)

Filed Feb. 8, 1971, Ser. No. 113,813

Term of patent 14 years

Int. Cl. D25—99

U.S. Cl. D28—1 C

FIG. 1 is a perspective view of a stanchion showing my new design;

FIG. 2 is a side elevational view thereof on an enlarged scale;

FIG. 3 is a top plan view thereof;

FIG. 4 is a bottom plan view thereof;

FIG. 5 is a perspective view of a modified form of stanchion; and

FIG. 6 is a side elevational view of the upper portion of such modified form.

I claim:

The ornamental design for a stanchion, substantially as shown and described.
